CLAIM

The ornamental design for a combined hydrogen ignitor and housing for wall mounting, substantially as shown and described.

DESCRIPTION

FIG. 1 is a front elevational view of a combined hydrogen ignitor and housing for wall mounting showing our new design;

FIG. 2 is a right-hand side elevational view of our new design;

FIG. 3 is a left-hand side elevational view of our new design;

FIG. 4 is a top plan view of our new design;

FIG. 5 is a rear elevational view of our new design, and FIG. 6 is a bottom plan view of our new design.

FIG. 1

FIG. 2

FIG. 3

FIG. 4

FIG. 5

FIG. 6
